OIL STICK WIPEE

Application September 6, 1939, Serial No. 293,590

4 Claims.

This invention relates to an oil stick wiper and has as its primary object the provision of a simple and economically constructed device for effecting wiping of oil sticks used in gauging the oil contents of the crank cases of motor vehicle engines.

Another object is to provide an effective means for supporting an absorptive wiping element in a fashion to facilitate its use in the wiping of an oil stick.

Another object is to provide a construction in the holder of the absorbent wiping element whereby the device may be readily attached to and removed from portions of a motor vehicle convenient to the reach of a person manipulating the oil gauge stick in effecting the oil gauging operation.

Another object is to provide a construction in the absorbent wiping element and its mounting whereby the element may be readily removed and replaced.

A further object is to provide an oil stick wiper in which a wiping pad of fibrous material formed with a slit leading from a margin thereof is held with the material at the inner end of the slit under a state of compression while the material at the outer end of the slit is comparatively loose so as to permit easy insertion of a stick in the outer end of the slit, and then subject the stick to a squeezing action when positioned at the inner end of the slit whereby the wiping action effected by drawing the stick through the inner portion of the slit is enhanced.

With the foregoing objects in view, together with such other objects and advantages as may subsequently appear, the invention is carried into effect as illustrated by way of example in the accompanying drawing, in which:

Fig. 1 is a perspective view of the device showing it as detached;

Fig. 2 is a view in section and elevation taken on the line 2-2 of Fig. 1 as viewed in the direction indicated by the arrows;

Fig. 3 is a diagram in perspective depicting the invention as applied beneath the hood of a motor vehicle;

Fig. 4 is a perspective view of the wiper depicting a mode of mounting same and illustrating the mode of operation thereof;

Fig. 5 is a perspective view illustrating another mode of mounting the wiper.

Referring to the drawing more specifically, 7 indicates generally an absorbent wiping element and 8 designates a holder therefor; the wiping element 7 comprising a rectangular or block shaped sheet of fibrous absorbent material such

as felt, which is formed intermediate its ends with a transverse straight slit 9 extending through one margin thereof to a point contiguous to but spaced from the opposite margin thereof. The holder 8 comprises a substantially U-shaped strip of sheet metal bent to conform to one edge and opposed sides of the wiping element 7; the strip being here shown as dimensioned to substantially conform to the element 7 so that its side edges will extend approximate the end edges of the element. In carrying out the invention the metallic strip comprising the holder 8 is formed intermediate its sides and ends with a slot 10 through which is exposed the slit 9 of the element 7.

As a means of securely fastening the wiping element between the side members 11 and 12 of the holder the element is formed with an opening 13 which is engaged by the shank of a stove-bolt 14 which is passed through opposed openings 15 in the side members 11 and 12 and through the opening 13 and is fitted on one end thereof with a nut 16 adapted to be screwed on the bolt to clamp the end portions of the side members 11 and 12 tightly against the wiper element 7 as particularly shown in Fig. 2. The end portions of the side members 11 and 12 are formed of transverse corrugations 17 and 18 which constitute jaws that are adapted to be clamped into engagement with the margin of a narrow sheet or panel 19 as shown in Fig. 4 or to be clamped into engagement with a rod or bar 20 as shown in Fig. 5.

In the application and operation of the invention the holder 8 is clamped to a support as above stated and as indicated in Fig. 3, convenient to the reach of an operator manipulating an oil stick 21 which is insertable in the crank case 22 of an engine in a well known manner; the device being positioned so that the open end of the slit 9 in the wiper will be presented in a direction to permit ready insertion of the stick laterally therein. To effect wiping of the stick the latter is inserted edgewise in the slit 9 and is then drawn lengthwise so that the sides of the slit will effect a wiping action on the sides and edges of the stick.

The sides of the metal holder being flexible, tightening of the nut 16 on the bolt 14 will act both to clamp the jaws 17-18 on the support 19 or 20 and to draw the outer end portions of the sides 11-12 toward each other so as to place the inner marginal portion of the wiper element 7 under compression so as to render the wiper more compact at the inner end of the slit 9 than

at the outer end thereof. By this arrangement the outer marginal portion of the wiper element will be sufficiently free and yieldable to permit easy insertion of the oil stick into the outer end of the slit; the portions of the wiper element forming the sides of the outer end portion of the slit readily spreading on advancing the stick therebetween. However, by compressing the inner marginal portion of the wiper element to render such portion more compact, the sides of the inner portion of the slit are rendered more resistant to spreading so that when the stick is advanced into the inner end portion of the slit and then drawn lengthwise therethrough the wiper element will closely and tightly conform to the stick and thereby effect a thorough wiping action thereon.

The inner end of the slit 9 is spaced outwardly from the ends of the slot 10 so as to present a wiping wall 23 to the advanced edge of the stick whereby on operating the stick when abutting the wall 23 the one edge as well as both sides of the stick will be wiped; then by withdrawing the stick and reversing it edgewise in the wiper the other edge of the stick may be wiped. However, the material of the wiper element being slightly resilient and being compressed and pinched between the sides of the holder with the sides of the slit abutting, the material forming the side walls of the slit will tend to protrude around both edges of the stick and accordingly in some instances will effect adequate wiping of both edges of the stick on drawing the stick lengthwise through the slit in a single operation.

Oil wiped from the stick will be absorbed in part by the wiper but in some instances a portion of the oil wiped from the stick may drip from the wiper which latter is accordingly preferably mounted where such drip will be caught where unobjectionable.

While the wiper element is preferably formed of an absorptive or semi-absorptive material it may also be formed of an elastic or flexible non-

absorptive material such as rubber, rubber composition, "Neoprene" and the like, which is capable of being flexed and compressed.

I claim:

5. In an oil stick wiper, a sheet of wiping material formed with a slit leading from an edge thereof, a U-shaped holder folded to extend astride said sheet having a slot in the folded edge through which said slit is exposed, means for 10 clamping the side members of said holder against said sheet, and jaws on the base of said holder adapted to be engaged with a support under the urge of said clamping means.
15. In an oil stick wiper, a flexible wiper pad formed with a slit leading from one edge thereof toward an opposed edge and terminating in spaced relation to the latter, a holder folded to extend astride said pad with the free end portions thereof protruding from said opposed edge, said holder having a slot in the folded edge and opposite sides thereof to expose said slit through the opposed sides and said folded edge of said holder.
20. The structure called for in claim 2 together with clamping means interconnecting the free end portions and extending through the unslit portion of the pad to clamp said pad therebetween adapted to hold one marginal portion of the pad under a greater state of compression than the opposite marginal portion through which the slit extends.
25. The structure called for in claim 2 together with clamping means interconnecting the free end portions of said holder to clamp said pad therebetween adapted to hold one marginal portion of the pad under a greater state of compression than the opposite marginal portion through which the slit extends, and means on the free ends of the sides of said holder cooperative 30 with said pad clamping means for engaging a support.
35. The structure called for in claim 2 together with clamping means interconnecting the free end portions of said holder to clamp said pad therebetween adapted to hold one marginal portion of the pad under a greater state of compression than the opposite marginal portion through which the slit extends, and means on the free ends of the sides of said holder cooperative 40 with said pad clamping means for engaging a support.

GREENE G. LESCHER.
